[57] CLAIM

The ornamental design for a table or the like, as shown and described.

DESCRIPTION

FIG. 1 is a perspective view of a table or the like, showing
my new design;

FIG. 2 is a side view thereof;

FIG. 3 is a top view thereof;

FIG. 4 is a bottom view thereof; and

FIG. 5 is a cross-sectional view taken along the line
5—5 of FIG. 1.
